UNITED STATES PATENT OFFICE.

SYDNEY R. WYCHERLEY, OF BROMLEY, ENGLAND, ASSIGNOR TO SPICER BROTHERS, LIMITED, OF LONDON, ENGLAND.

LOOSE-LEAF BINDER.

1,398,214.

Specification of Letters Patent. Patented Nov. 22, 1921.

Application filed March 10, 1921. Serial No. 451,243.

To all whom it may concern:

Be it known that I, SYDNEY RENODEN WYCHERLEY, stationer, a subject of the King of England, residing at 25 Holligrave road, 5 Bromley, Kent, England, have invented certain new and useful Improvements in Loose-Leaf Binders, (for which I have filed an application in England, No. 1,857 of 1920, filed Jan. 20, 1920,) of which the following 10 is a specification.

This invention relates to loose leaf binders in which the leaves are strung upon flexible thongs or cords and are held together by two clamping bars which are 15 drawn together by tightening or winding up the thongs or cords. The object of the invention is to provide improved means for connecting the covers to the back of the file and for connecting and holding in alignment 20 the clamping bars.

The accompanying drawings show one embodiment of the invention. Figure 1 is a rear elevation of the binder in its closed condition and adjusted to take the minimum 25 number of sheets. Fig. 2 is a top view corresponding to Fig. 1; Fig. 3 is an inside elevation of the binder in its open condition and adjusted to take about the mean number 30 of sheets; Fig. 4 is a top view corresponding to Fig. 3. Fig. 5 is a perspective view of the complete binder, omitting the sheets and the mechanism for drawing together the clamping bars which may be of any kind and does not form part of the invention. Fig. 5^a shows a detail. Fig. 6 is a section through one of the pivots connecting the cover of the binder to the cover 35 of the corresponding clamping bar. Fig. 7 is a detail view of the removable cover of 40 the clamping bar. Fig. 8 is a fragmentary view of the clamping bar showing means for attaching the cover. Figs. 9 and 10 are sections on line IX—X of Figs. 7 and 8.

It will be seen from Fig. 5 that covers 1 45 and 2 of the binder are not as usual connected by a flexible back made of leather or fabric, but are hinged direct at 3 and 4 respectively, to the clamping bars 5 and 6. The latter are directly connected to the two 50 halves 7 and 8 of the telescopic back. The telescopic back is so constructed that it entirely covers the inner edges of the sheets. There is therefore no necessity to bind the 55 two covers in the same manner as the covers of a book are bound. The two covers are solely connected through the telescopic back.

The back consists of two telescoping parts 7 and 8. The part 7 consists in the construction shown of the plate 9 having a flange 10 along its long edge and two short 60 flanges, 11 and 12 at the short sides. The other half of the back, viz. 8 similarly consists of a plate 11^a having flanges 13 and 14 which have inset portions 15 and 16 forming guides for the flanges 11 and 12. 65 The part 8 may be connected to or integral with the clamping bar 6. The flanges 13 and 14 have double pin and slot engagement with the flanges 12 and 11 as may be seen from Fig. 4. Flange 13 is provided with 70 two slots 17, into which take two pins 18 of the flange 12. The two halves 7 and 8 of the back are thus very firmly guided in one another and are consequently capable of holding the clamping bars in alignment 75 even in case an excessive pressure should be put on the clamping bars. It will also be seen that although the back is so constructed as to cover entirely the inner edges of the sheets and to hold efficiently the clamping 80 bars in alignment, it hardly increases the total length of the ledger as the inner edges of the sheets may be brought close to the parts 9 and 11.

The construction of the mechanism for 85 winding up the thongs does not form part of the invention and may be of any suitable kind. It is assumed that the ends of the thongs 20, 20 are permanently secured in the clamping bar 6, and that the other ends are 90 secured to and wound upon a shaft 19 mounted within the U shaped clamping bar 5. The U shaped clamping bar 5 may be permanently secured to the flange 10 in any 95 suitable manner.

The cover 2 is hinged direct to the clamping bar 6 at 4, 4. For this purpose metal flaps 21, 21 are fixed to the edges of the cover 2 and are provided with eye portions 22 through which are passed pins 23 extending through suitable holes in end flanges of the clamping bar 6. The flaps may be provided with serrated edge portions and may be secured to the covers by pressing the serrated edges into the covers, as shown in Fig. 5^a.

As the mechanism mounted within the clamping bar 5 should remain open to inspection, the other cover 1 is not hinged directly to the clamping bar 5, but is hinged to a removable cover 24 of the clamping bar 110 (see Figs. 7 and 9). The connection be-

tween the cover 1 and the cover 24 is effected through metal strips 25 fixed to the edges of the cover and provided with eye portions 26. The pins 27 which connect 5 the parts 24 and 26 and form the pivots are in this case hollow to allow of the insertion of a key or other tool for operating the mechanism mounted inside the clamping bar (see Fig. 6). The cover 24 is detachably secured to the clamping bar 5 in the following manner. Within the clamping bar are arranged pins 28 which are adapted to snap into holes 29 of the cover 24. Preferably three pins are arranged on each side, 15 two opposite pins being mounted on a common spring carrier 30. These springs may be constructed sufficiently strong to serve also for reinforcing the clamping bar. If it is desired to inspect the mechanism within 20 the clamping bar the pins are pressed inwardly by hand, and the cover 1 with the cover 24 is then slid off.

An important advantage of the invention resides in the fact that it is not necessary to bind the covers in the usual manner. All the parts of the binder may be made separately and may be connected very rapidly and solidly, and a comparatively large number of sizes may be made from 25 a comparatively small number of stock sizes of the various component parts.

I claim—

1. A loose leaf binder comprising clamping bars, one of said bars comprising detachably associated housing sections, leaf-engaging means connecting one of the housing sections with the other clamping bar, and a cover hinged to the other housing section.

2. A loose leaf binder comprising clamping bars, one of said bars comprising interfitting channel sections, means for detachably connecting the sections, flexible thongs between the other clamping bar and one of the channel sections, and a cover pivotally connected to the ends of the other of said channel sections. 45

3. A loose leaf binder comprising leaf clamping bars, thongs connected to one bar, the other bar comprising a housing composed of detachably associated overlapped channel sections, means carried by the inner section and projecting outwardly therefrom and detachably engaging the outer of the overlapped sections for securing the same together, a shaft within the housing, and means for connecting the thongs to the shaft so as to wrap them thereupon when said shaft is rotated. 50 55

4. A loose leaf binder comprising leaf clamping bars, thongs connected to one bar, the other bar comprising a housing composed of detachably associated overlapping channel sections, bowed springs within the housing having outstanding studs that pass 60 through the overlapped sections for securing the same together, a shaft within the housing, and means for connecting the thongs to the shaft so as to wrap them thereupon when said shaft is rotated. 65 70

In testimony whereof I have hereunto set my hand in the presence of two witnesses.

S. R. WYCHERLEY.
